CLAIM

The ornamental design for a tool kit box, as shown and described.

DESCRIPTION

FIG. 1 is a first perspective view of a tool kit box showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a left side view of another state of the tool kit box thereof;

FIG. 10 is an exploded view of the tool kit box thereof;

FIG. 11 is another exploded view of the tool kit box thereof;

FIG. 12 is another perspective view thereof, shown in a state of use; and,

FIG. 13 is another perspective view thereof, shown in an alternate state of use.

The broken lines shown in the drawings depict portions of the tool kit box that form no part of the claimed design.

1 Claim, 13 Drawing Sheets
